Primary Examiner — John Windmuller*Assistant Examiner* — Steven J Czyz(74) *Attorney, Agent, or Firm* — Knobbe, Martens, Olson & Bear, LLP(57) **CLAIM**

The ornamental design for a rack for anodizing metal components, as shown and described.

DESCRIPTION

FIG. 1 is a front perspective view of a rack for anodizing metal components of the present invention;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.
The broken lines depict portions of the article that form no part of the claimed design.
